UNITED STATES PATENT OFFICE.

EDWARD B. ROBY, OF TROY, NEW YORK, ASSIGNOR TO STANLEY M. STONE, OF COHOES, NEW YORK.

FOLDING-MACHINE.

1,260,060.

Specification of Letters Patent. Patented Mar. 19, 1918.

Application filed March 1, 1916. Serial No. 81,306.

To all whom it may concern:

Be it known that I, EDWARD B. ROBY, a citizen of the United States, and resident of Troy, county of Rensselaer, and State of New York, have invented certain new and useful Improvements in Folding-Machines, of which the following is a specification.

The present invention relates to folding machines of the general character comprising inwardly slideable folders, a downwardly and upwardly movable cross-head and attached die, a vertically movable bed-plate and means for assembling, operating and supporting said parts; the machines adapted for folding the edges of moistened fabric blanks over the edges of the die and heating and ironing said blanks, whereby they are made ready for the sewing machines and the process of manufacture is facilitated.

The invention has for its principal object to provide means for operating the said parts which are of very simple, durable and inexpensive construction and which are assembled and arranged in such novel correlation that they may be successfully operated by the employment of but few motions and a minimum of motive, and also, manual force; a further object being to conserve expense and time by the production of a maximum quantity of product in a minimum period of time.

The invention is especially applicable for turning the edges of collar and cuff blanks, but may be employed for turning the edges of any fabric blanks, for instance, patch-pocket blanks for uniforms and overalls.

In carrying out my invention I use substantially the above named parts, common to folding machines now in public use, excepting that I employ a die of novel construction, a novel assemblage of parts and a novel operating means comprising a pneumatically actuated reciprocating piston, a valve device, a recessed piston-rod, levers operated by said piston-rod, a pedal of novel construction for operating said valve device, a rack, pinion and beveled gear mechanism, and a governor to control motion and pre-

vent abrupt impingement of the moving parts which are adapted to be pressed together, all as will be hereinafter fully described and specifically set forth in the annexed claims.

In the accompanying drawings forming part of this specification, Figure 1 is a vertical sectional view of my improved machine, taken through the center thereof. Fig. 2 is a detail sectional plan view taken on the line 2—2 of Fig. 1. Fig. 3 is a cross section taken on the line 3—3 of Fig. 2. Fig. 4 is a detail sectional plan view taken on the line 4—4 of Fig. 1. Fig. 5 is a cross sectional view taken on the line 5—5 of Fig. 4. Fig. 6 is a front view of the upper part of my improved machine showing parts thereof broken away in sectional elevation. Fig. 7 is an inverted sectional plan view taken on the line 7—7 of Fig. 6. Fig. 8 is a fragmentary detail, in plan, of one corner of the machine. Fig. 9 is a perspective view of the machine. Fig. 10 is a face view of the die and cross-head thereof forming part of my invention. Fig. 11 is a cross sectional view taken on the line 11—11 of Fig. 10; and Fig. 12 is a similar view taken on the line 12—12 of Fig. 10.

In the example of my invention as illustrated by the accompanying drawings, A represents a frame-work of adaptable design and construction and having a central opening through its top a, for accommodating a vertically movable bed-plate B, which is adapted to be heated by means of a suitably insulated high resistance conductor b, adapted for electrical connection with a source of electrical supply not shown in the drawings, as the means for heating the bed-plate form no part of the present invention; and, other heating agents may be employed if desirable.

Secured to and located on a vertical central line beneath the top a, of the frame-work A, is a cylinder C, adapted for receiving a motive operating element, as compressed air, and containing a reciprocating piston D having a piston rod E, which passes through the head c, of the cylinder.

C, and is provided with a contracted extension *e*, said extension is in connection with a reciprocating piston F, located within an oil-containing cylinder G, said cylinder also 5 secured to the framework A, and located in vertical central alinement beneath the cylinder C. The two said pistons are maintained in their normal positions, illustrated by Fig. 1 of the drawings, by means of a 10 spiral spring H, located between a collar *h*, secured to the extension *e* of the piston E, and the stuffing box *g*, of the cylinder G.

Resting on the collar *h*, is a cross-head I 15 having integrally formed vertical arms which are each provided with a lateral extension *i*, which engages beneath the head *c* of the cylinder C, to limit the upward stroke of the pistons D and F. This cross-head is adapted for operating the bed-plate herein- 20 after described.

Pivots secured between integral extensions *f*, forming part of the cylinder head *c*, is a lever J, having a downwardly and inwardly extended arm *j*, to which is pivoted 25 a roller 2, this roller normally bears within a cam-like recess 3 formed in the piston-rod E, and, during the operation of the device, hereinafter described, engages a shallow recess 1. The lever J also has an eye 4 in its 30 outer, or free end, for engagement with one end of a spiral spring K which is connected at its other end to the lower part of the framework A.

Connected, by means of the pivots 5, with 35 the lever J, near the free end thereof, is an adjustable connecting-rod L, which may be either shortened or lengthened by means of the turn buckle 7. This rod L is pivoted, at its upper end, to an extension *m* of a lever 40 M, which is in pivotal engagement between bearings 6, said bearings are extended upwardly and rearwardly from the top *a* of the framework A, and the lever M is pivoted between said bearings by means of set- 45 screws N, which are in screw-threaded engagement with the bearings 6, and have respectively a conical end which is in frictional engagement with a correspondingly cone-shaped recess in the hub 7. By this 50 means tension may be provided to prevent jerky or abrupt movements of the lever M, and all jarring action is obviated. The upper end of the lever M is bifurcated and is secured to the cross-head O of the die P, 55 by means of the screws *o*.

Pivots secured between integral extensions 8 of the cylinder head *c*, which are located diametrically opposite the extensions *f*, is a lever Q having a downwardly and inwardly extended arm *q*, to which is pivoted 60 a roller 9; this roller bears within a cam-like recess 10, formed in the piston rod E, and the outer, or free end of the lever Q is provided with an eye 11, which engages one

end of a spiral spring R, said spring being 65 secured at its other end to the lower part of the framework A.

To the lever Q, near the free end thereof, is pivoted a toothed rack S, which extends upwardly and engages a toothed pinion T, 70 said pinion being secured to a horizontal shaft U, which is journaled through a hanger *u*, at its central part, and at its ends, through downwardly and outwardly directed arms *v*, of depending bearings V, located one at each corner of the front part of the top *a* of the framework A. An anti-friction roller 12, having an annular flange 13, engages the rack S to maintain connection between said rack and the pinion T. 80

Each bearing V has extended downwardly therethrough a vertical shaft W, having at its upper end a circular head *w*, and at its lower end a beveled gear wheel X, which meshes with a similar beveled gear wheel Y fixed to the shaft U, whereby rotary motion imparted to said shaft U, simultaneously turns the shafts W. Each head *w*, is provided with a plurality of openings 14, which are arranged eccentrically at differential distances from the center of the shaft, these openings are for engagement with a pin 15 which passes through a connecting link 16 which is bolted to the folder 17, whereby when the shaft W is turned the folder is moved inwardly. The beveled gear wheels X, are respectively held to their shafts W by means of a set screw *x*, whereby the shaft W may be turned to a sufficient degree to insure proper correlation with the link 16, to gage the distance of movement required for the folder. 90

The folders 17, are arranged in the manner common to folding machines as shown in Fig. 9, and are adapted to move inwardly, 105 and they respectively have a thin plate 18 for folding the edges of the blank over the die; they are also held close to the frame top *a*, by means of adjustable presser fingers 19 which are secured by means of the 110 screws 20.

Fastened to each end part of the shaft U is a pinion Z; these pinions respectively engage a cross rack 21 having downwardly directed teeth on the lower part of its forward end and outwardly directed teeth on the side of its rearward end. The last named teeth engage pinions 22, secured respectively to a vertical shaft 23 and located one at each rearward corner of the top *a* 120 and laterally opposite to the beveled pinions X, whereby when rotary motion is imparted to the pinions Z, the pinions 22 and X are caused to rotate and operate the folders. The shafts 23 are of construction similar to 125 the shafts W, connecting links 16 also being provided to connect said shafts 23 with the folders 17. Anti-friction rollers 24, are

also provided to keep the racks 21 in alignment.

The cylinder C communicates with a valve box 25, by means of a port 26 which leads 5 into a passage way 27. Within said passage way is a valve 28, having a thin stem 29, which is connected to a rod 30, the upper end of which acts as a means for opening and closing the exhaust, said rod 30 engaging 10 a lateral link 31 which is in pivotal engagement with the upper end of a rod 32. The rod 32 extends downwardly and is pivoted to an extension 33, which extends from the inner end part of an operating pedal d, 15 which is maintained in its normal horizontal position by means of the spiral spring 34 which is connected at one end to the cross link 31 and at the other end to the lower part of the framework A. The pedal d is 20 pivoted to hangers 35 of the framework A, and it embodies two sections 36 and 37, the section 37 pivoted to the section 36 by means of the vertical bolt 38, and having a downwardly extended curved part for direct engagement 25 with the foot of an operator. It will be noted that this downwardly extended part, being near the floor, admits of the operator working the pedal by the simple use of the toe part of the foot with the heel 30 resting on the floor, and the short distance which the part 39 is required to travel makes the device operable with but little manual labor, the swinging arrangement of the part 37 also enables the operator to fix the pedal 35 in any required position necessary to facilitate his movements.

Leading into the valve box 25 is a supply pipe 40, which leads from any suitable source of supply, the outlet from said pipe 40 being normally closed by the valve 28, as shown by Fig. 2 of the drawings. An exhaust pipe 41 leads outwardly from said valve box having its inlet normally open.

The oil-containing cylinder G is in lateral 45 communication with a closed chamber 42, by means of passage ways 43, 44 and 45. These passage ways are adapted to be choked by means of the screws 46, 47 and 48, for the purpose of governing and regulating the 50 movements of the piston F during its reciprocating movements. Said piston being provided with an opening 49, which is closed during the downward movement of the piston and opened during the upward movement 55 thereof.

The die forming part of my invention comprises three sections 51, 52 and 53, and a cross-head 54. The cross-head is of rigid construction, having a deep groove 55 leading 60 through its entire length; and the sections 51, 52 and 53 each comprise a sheet metal plate 56, forming the die proper, and a rigidly attached solid metal tongue 57, for engagement with the groove 55, of the cross-

head 54. The two end sections are respectively beveled at their inner end part and are provided with a recess 58, containing a spiral spring 59 which bears against a collar 60 on a rod 61^a, this rod bears against the top of the cross-head 54 and maintains the 65 sections 51 and 52 in alignment when the die is pressed downwardly upon the blank to be turned. When it is desired to remove the blank, the operative grasps same at each end and pulls it downwardly; this movement 70 causes the sections 51 and 52 to swing in the direction of the arrows, shown in Fig. 10 of the drawings, contracts the die in length and permits of ready removal of said blank. The sections 51, 52 and 53 are each held to 75 the cross-head 54 by means of a screw 58^a which may engage any one of the openings 59^a, whereby the length of the die may be varied, and a scale 62^a is placed on the face of each end of the cross-head to gage the adjustment required. When the sections 51 and 52 are moved away from each other for any considerable distance a section 53 of greater width than the one shown in the drawings is substituted, whereby proper 80 space between the sections may be maintained.

The bed-plate B, employed in conjunction with the die for pressing the blanks, normally rests on pins 61 which extend 85 through the levers 62 employed for lifting said bed-plate. These levers are pivoted to the framework A and are held normally in horizontal position, shown in Fig. 6 of the drawings, by means of the springs 63. As a 90 means for operating the said levers 62, rods 64 having heads 65, depend through openings of the inner ends of the levers and pass through the cross-head I. These rods may be adjusted to the proper length by means of 95 thumb nuts 66, whereby the movements of the bed-plate may be gaged.

In the operation and use of the invention, downward pressure exerted upon the pedal d, at its forwardly and downwardly extended part, lifts the valve 28 and allows access 100 of compressed air to the cylinder C, at the same time the exhaust is closed by the upper end of the rod 30. This causes a downward movement of the piston D and exerts a cam-like action upon the roller 2 of the lever J, forcing the free end thereof to swing upwardly and, through the medium of the rod L, imparting a downward movement to the cross head O and its die P. Thus when a 105 blank is placed upon the bed-plate B, the first action is to press and hold the same thereon. Further movement of the piston D and its rod E imparts upward swinging movement to the lever Q whereby the rack, 110 pinion and bevel gear mechanism, hereinbefore described, operates to move the folders and turn the edges of the blank over the die 115 120 125

in the common and well-known manner. After these operations are completed the lower end of the enlarged part of the rod E strikes the cross-head I, and through the medium of the rods 64 and levers 62 lifts the bed-plate B against the die to perform the pressing operation, the recess 1 allowing the die sufficient yielding and upward movement to prevent jamming and jarring.

10 The retarding action of the oil in the cylinder G, against the piston F prevents abrupt movements of the parts and causes smooth action throughout all of the movements, the degree of retarding influence being controlled by means of the screws 46, 47 and 48.

15 While I have described and shown a pneumatically operated construction, I do not confine myself to the use of pneumatic power, as steam may be employed if found desirable; neither do I confine myself to the specific details of construction and arrangement of parts, as I believe under the spirit and scope of my invention, I am entitled to 20 use structural variations necessary for folding blanks of different kinds and proportions.

25 The bed-plate B is generally maintained in horizontal position, but if for any reason it is desired to slightly tilt it, as for instance, to place it in perfect alinement with the die or to allow for inequalities in the material being operated upon, the thumb-nuts 66 may be adjusted on the rods 64 to tilt it at either 30 end.

35 Having thus described my invention, what I claim as new, and desire to secure by Letters Patent, is:

1. In a machine of the class described, a 40 framework, a reciprocating heated bed-plate and means for supporting the same, reciprocating folder plates, and a reciprocating cross-head and die, in combination with means for operating said reciprocating parts comprising a cylinder, a power operated piston, a valve mechanism, a piston rod having recesses which each have a vertical and two beveled faces, a lever mechanism operable by means of said recessed rod, a rack, pinion and beveled gear mechanism, a foot lever for operating said valve mechanism, and a retarding device for governing the movements of said piston.

2. In a folding machine of the class described, the combination, of a framework, 55 folders, a cross-head and die and a reciprocating heated bed-plate; with a power-operated reciprocating piston, a valve device, a recessed piston-rod, levers operated by said rod, a foot lever for operating said valve device, and a rack, pinion and beveled gear mechanism.

3. In a folding machine, the combination, 60 of a framework, an upwardly and downwardly movable cross-head and die, and a

reciprocating bed-plate; with a power-operated reciprocating piston, a cylinder therefor, a valve device, a piston-rod having recesses each having a vertical and two beveled faces, levers operated by said rod, a foot lever for operating said valve device, a retarding device connected with said piston-rod, a rack, pinion and beveled gear mechanism, and means supporting said parts.

4. In a folding machine, the combination, 65 of a framework, folders, an upwardly and downwardly moving cross-head and die, and a reciprocating heated bed-plate; with a power-operated reciprocating piston, a cylinder therefor, a valve device, a piston-rod having recesses each having a vertical and two beveled faces, levers operated by said piston-rod, a foot lever having a laterally swinging pedal, said foot lever adapted for operating said valve device, a retarding device, and means connecting said retarding device with said piston, a rack, pinion and beveled gear mechanism, and means supporting said parts.

5. In a folding machine, the combination, 70 of a framework, an upwardly and downwardly moving cross-head and die, folders and a reciprocating heated bed-plate; with a power-operated reciprocating piston and cylinder therefor, a piston-rod having recesses each having a vertical and two beveled face parts, said piston-rod having an extension, and a valved piston connected to said extension, and an oil-containing cylinder therefor, said valved piston adapted for controlling the movements of the first-named piston, and two levers having rollers engaging said recesses of the piston-rod, one of said levers adapted for operating said cross-head and die and the other adapted for operating said folders, and a rack, pinion and beveled gear mechanism, and a foot lever for 75 operating said valve mechanism, said foot lever having a downwardly directed laterally swinging pedal, and spring-means for controlling the said parts.

6. A cross-head and die for use in folding machines of the class described, comprising a head having a longitudinal groove, a central fixed die section, and end rocking die-sections each embodying a die-plate and a tongue, the tongues of said end die sections each having an upper surface part abutting against the horizontal wall of said groove and an upper beveled surface part, and pivot means at the point of intersection of said parts, whereby said sections may be caused to rock.

7. A cross-head and die for folding machines of the class described, comprising a head having a longitudinal groove in its under surface, a central die section embodying a plate and a tongue in fixed engagement with said groove, and adjustable swinging end sections each embodying a plate and a

tongue, said tongues engaging said groove and each having a horizontal and a beveled part, and means for pivoting the swinging die sections and for adjustably securing them to the head, and spring means for maintaining said swinging sections in normal parallel engagement with said groove.

5 In testimony that I claim the foregoing

as my invention, I have signed my name, in 10 presence of two witnesses, this twenty-fifth day of February, 1916.

EDWARD B. ROBY.
